UNITED STATES PATENT OFFICE.

CHARLES H. SIMMONS AND JAMES R. HEPBURN, OF BROOKLYN, ASSIGNORS
TO THE NEW YORK AND NEW HAVEN AUTOMATIC SPRINKLER COM-
PANY, OF NEW YORK, N. Y.

AUTOMATIC FIRE-EXTINGUISHING SYSTEM.

SPECIFICATION forming part of Letters Patent No. 416,867, dated December 10, 1889.

Application filed April 8, 1889. Serial No. 306,477. (No model.)

To all whom it may concern:

Be it known that we, CHARLES H. SIMMONS and JAMES R. HEPBURN, both citizens of the United States, and residents of Brooklyn, in the county of Kings and State of New York, have invented a new and useful Improvement in Automatic Fire-Extinguishing Systems, of which the following is a specification.

This invention relates more particularly to
10 the automatic fire-extinguishing systems known as the "dry-pipe" systems, in which the gangs of pipes running throughout the building to be protected and provided with the closed sensitive sprinklers are connected
15 to a common supply-pipe leading from an elevated tank or other supply of water under pressure, and provided with a valve by which the water is normally excluded from the sprinkler-pipes and the air in the sprinkler-
20 pipes, together with the communicating main supply-pipe, is normally maintained at a different pressure from the atmosphere, so that in case any of the sprinklers are opened by fire near the same the air-pressure in the
25 pipes will change to that of the atmosphere, which change of pressure is arranged by automatic controlling devices to open the main water-supply valve, thereby allowing the water to throw itself from such of the sprinklers
30 as are opened upon the fire and extinguish the same.

Devices for automatically opening the main water-supply valve when the abnormal air-pressure in the pipes is relieved have heretofore been employed, consisting of a diaphragmatic chamber in communication with the closed pipes and having its movable diaphragmatic wall in operative connection with the secondary valve of an automatic differential governor-valve used as the main supply-valve.

The main object of our invention is to provide for the use of a common single-acting valve as the supply-valve and the direct and certain operation of the supply-valve on the outbreak of fire.

A further object is to conveniently provide for the locking of the main supply-valve in an open position, so that the system can be

used as a wet system—that is, with the water 50 filling the sprinkler-pipes.

To these ends the invention consists of certain novel devices for operating the main supply-valve, for locking the same against the pressure of the water and restraining the 55 valve-operating devices, and for automatically releasing both the valve-locking devices and the valve-operating devices simultaneously with the outbreak of fire, all substantially as hereinafter described, and particularly pointed out in the claims.

Reference is to be had to the accompanying drawings, forming part of this specification, in which—

Figure 1 is a sectional perspective view of 65 part of a building provided with an automatic fire-extinguishing system embodying our invention. Fig. 2 is an enlarged elevation, partly sectional, of the main water-supply valve and automatic valve-controlling devices of the said system. Fig. 3 is a detail sectional plan view on the line X X, Fig. 2. Fig. 4 is a detail sectional plan view on the line Y Y, Fig. 2.

The upper end of the main water-supply 75 pipe A here shown is presumed to be connected with an elevated water-tank or other water-supply under pressure, and with the pipe A are connected the distributing-pipes B, which are carried throughout the structure 80 C to be protected, and are provided at intervals with sprinklers D, of any appropriate pattern, closed usually by sensitive solder, so as to be opened automatically by heat.

The main supply-pipe A is provided between the sprinkler system and the water-supply with a valve E, by which the water is normally excluded from the sprinkler system, and which is to be opened automatically to permit the water to flow through the sprinkler 90 system when any of the sprinklers are affected by heat from an adjacent fire, all after a well-known fashion. To secure the action necessary to the automatic operation of the main valve E from such a rise in temperature at 95 any point, we have illustrated a contrivance such as is used in a common dry-pipe system. This comprises an air-chamber F, con-

nected by a branch pipe G to the part of the main pipe A in constant communication with the closed sprinkler system, and having a movable diaphragmatic wall H, which is affected by the air-pressure within the closed pipe system. This internal pressure is presumed in this instance to be maintained normally at a higher point than the atmosphere by a connecting air-pump I and the degree of pressure indicated by a pressure-gage J. The diaphragm H is thus pressed normally outward.

With the diaphragm H is connected by a link H' a movable bar H², which normally supports a drop-arm H³, and also through a connecting-chain H⁴ a weighted lever K, the arrangement being such that when the pressure within the closed pipe system falls by the opening of any of the sprinklers the return of the diaphragm H will permit the self-acting lever K to fall.

The valve E, which we prefer to use as the main supply-valve, is one of the well-known self-releasing "gate" pattern, the stem E' of which works lengthwise in the stuffing-box L, and it is in the devices for locking this valve in closed position and for causing the same to open automatically with the operation of the self-acting lever K that our invention principally consists.

The stem of the valve E is formed with a series of annular serrations M, and one section L' of the stuffing-box L surrounding the serrated stem is arranged to slide laterally between the ends of the remaining sections as guides, and is formed on its inner face with serrations corresponding to and adapted when moved inward to engage, as a bolt, those on the valve-stem E', and thus lock the same, with the valve E, in place.

The sliding section or bolt L' has an arm L³, which is pivotally connected to an elbow-arm K' of the lever K, so that normally the bolt L' will be held in locking position, but when the lever K falls, as before described, will be retracted, and the valve E thus freed.

The freed valve-stem E' is arranged to be drawn outward and the valve E opened, in this instance, by a weight N, acting through connected chains O O', which weight is normally sustained independently of the bolt L' by an extra chain O², having, by preference, an eye or loop O³, which is held against lateral movement by a fixed holder P, and is normally engaged by a finger-catch Q, carried by the arm K' of the lever K, so that when the lever K falls the catch Q will be disengaged from the chain or cable O², and the weight N thus allowed to fall and open the valve E. It

is generally preferred to leave the valve-operating chain O' slack when the weight-chain O² is caught, so that when the latter is released the weight will acquire enough momentum before the strain of the valve is felt to easily overcome the initial resistance of the valve. This initial resistance being overcome, the valve E, being self-releasing, will easily open.

In order that the valve E may be locked more securely, as when it is to be left always open in using the system as a "wet" system, we form both the fixed and movable sections of the stuffing-box L with registering external screw-threads and adapt the gland S to be screwed as a sleeve down over both, so as to hold the bolt-section L' in engagement with the valve-stem E'.

Our improvement is similarly applicable to the electric dry-pipe systems, in which the operating-lever K would be released by electrical action.

We claim as new and desire to secure by Letters Patent—

1. In an automatic fire-extinguisher, the combination, with the water-supply valve, of a weight and connections to operate the said valve, a chain to support the said valve-operating weight, a weight-operated lever provided with a catch to engage and restrain the weight-supporting chain and a bolt or catch to engage and restrain the valve-stem, a support for the said weighted lever, and a lever-releasing device operated by heat, substantially as described.

2. The herein-described valve-lock, consisting of serrations on the valve-stem and a serrated bolt adapted to engage the said serrations on the valve-stem, as set forth.

3. The valve-lock herein described, consisting of a serration or shoulder on the valve-stem, a stuffing-box surrounding that part of the valve-stem and having a lateral opening, a bolt working through said opening to engage the shoulder or serration of the valve-stem, and a sleeve adapted to screw on the stuffing-box over a part of the said bolt, as set forth.

4. The combination, with the serrated stem of the main valve, of a stuffing-box a section of which is serrated to correspond with the stem and is movable laterally, and means for locking the said movable section in place, substantially as described.

CHAS. H. SIMMONS.
JAMES R. HEPBURN.
